UNITED STATES PATENT OFFICE.

THOMAS B. JEFFERY, OF CHICAGO, ILLINOIS.

DESIGN FOR A BICYCLE-FRAME REINFORCE.

SPECIFICATION forming part of Design No. 28,402, dated March 22, 1898.

Application filed December 13, 1897. Serial No. 661,754. Term of patent 7 years.

To all whom it may concern.

Be it known that I, THOMAS B. JEFFERY, a citizen of the United States, residing at Chicago, county of Cook, and State of Illinois, have invented a certain new and original Design for a Bicycle-Frame Reinforce, which is fully set forth in the following specification, reference being had to the accompanying drawing, forming a part thereof.

This design relates to a fitting for uniting and reinforcing the tubular bars of a bicycle-frame, commonly called a "bicycle-frame reinforce." It is illustrated in the drawing, which is a perspective view, and is characterized by the shape and appearance of the reinforce-arms A A, which project from the cylindrical portion A' of the fitting. These reinforce-arms are in the form of a conventional

spear or a tapered form pointed at the extremity and indented at the sides a short distance back of the extremity and in general bearing a resemblance to an arrow having lateral projections back of the head and curved about the axis of the cylindrical portion A'. 20

I claim—

The design for a bicycle-frame reinforce herein shown and described.

In testimony whereof I have hereunto set my hand, at Chicago, Illinois, in the presence of two witnesses, this 20th day of November, 30 1897.

THOS. B. JEFFERY.
